UNITED STATES PATENT OFFICE.

DAVID PETRI-PALMEDO, OF BRIDGEPORT, CONNECTICUT, ASSIGNOR TO ELECTRIC COM-
POSITOR COMPANY, OF NEW YORK, N. Y., A CORPORATION OF NEW JERSEY.

TYPOGRAPHICAL MACHINE.

1,249,477.

Specification of Letters Patent. Patented Dec. 11, 1917.

Application filed August 30, 1915. Serial No. 47,963.

To all whom it may concern:

Be it known that I, DAVID PETRI-PALMEDO, a citizen of the United States, residing at Bridgeport, in the county of Fairfield 5 and State of Connecticut, have invented a certain new and useful Improvement in Typographical Machines, of which the following is a full, clear, and exact description.

This invention relates to circulating 10 matrix typographic machines, and particularly to machines of this kind which contain a plurality of magazines, from any one of which matrices may be assembled at will; and which also contains distributing mechanism 15 for automatically returning said matrices to the proper channels of the magazines in which they severally belong.

It has long been customary to provide single magazine circulating matrix typographic 20 machines with a holder for "sorts" matrices, located conveniently for the operator; and with means whereby to cause the automatic delivery to said holder of any "sorts" matrices used in matrix lines. It might be here 25 explained that "sorts" matrices are matrices having characters which are so seldom required in a matrix line that the magazines are not formed with channels for containing them, and which therefore will not be delivered 30 into any magazine channel by the distributor. Nevertheless, such "sorts" matrices are not infrequently required in a line. The sorts holders heretofore used have been receptacles in which the sorts matrices are 35 arranged in haphazard order, but so exposed that the operator may readily see and locate the one he wants to use, and may easily remove it from the holder and insert it at the proper point in a matrix line which is being 40 assembled.

If, however, one should put into a multiple magazine typographic machine, a single sorts holder and the mechanism for returning sorts matrices thereto, such as has served 45 for a single magazine machine, the sorts matrices of different styles or faces would soon become so mixed up that much of the operator's time would be wasted in seeking, through the mixed mass of sorts matrices, to 50 discover one of the particular face or style required.

It is the primary object of this invention to provide means for making it easy for the operator to quickly find and get hold of the 55 sorts matrix of the particular face required.

To this end the invention involves the use of a plurality of sorts holders, preferably one for each magazine, and a plurality of tubes or conductors which severally discharge into these sorts holders, and which 60 are so arranged at their receiving ends that the distributing mechanism may deliver each sorts matrix into that tube which is associated with that sorts holder designed to hold them. 65

In the accompanying drawing, the invention is shown in the preferred form, and by way of example, as applied to a typographic machine having plural magazines supported on a swinging frame, and associated distributing mechanism substantially as shown and described in the application filed by David Petri-Palmedo and Edward F. Goddard, October 16th, 1913, Serial No. 795,398; and the accompanying drawing shows only 70 so much of the machine of said prior application as is necessary to disclose in what manner the present invention may be applied thereto.

In the drawing, Figure 1 is a front elevation of the left side of the swinging magazine frame, the magazine supported thereby, and of the lower part of the distributing mechanism, with the present invention applied thereto. Fig. 2 is a sectional side elevation of the corresponding parts, the section being in the plane indicated by lines 2—2 on Fig. 1. Fig. 3 is a side elevation from the left side of the mechanism shown in Fig. 1. Fig. 4 is a sectional view taken on line 4—4 90 of Fig. 2.

The parts shown of the particular machine to which, by preference, this invention is applied, and for which the invention in the particular form shown is designed, are as 95 follows:

A magazine supporting frame 10 is pivotally connected at its upper end to fixed frame work 12 of the machine, so that said frame may be swung forward and backward by suitable mechanism (as for example, the rotatable pinion 13 and the rack segment 14 on said swinging frame), to bring any one of the four magazines 15 which said frame supports, into operative 105 relation with the matrix releasing mechanism.

On this swinging frame, above the magazines, is the magazine determining part of the distributor; and above that mounted on 110

a fixed frame member 16 is the character determining part of the distributor. The drawing shows the lower left hand corner of the fixed frame member, and a few of the 5 matrix delivering lower ends of the distributor channels 21 supported thereby, and some of the switches 22 in said channels. It also shows the left side of the swinging frame 10 and some of the magazine determining 10 channels 23^a, 23^b, 23^c and 23^d thereon, and some of the switches 24 in said channels.

The sorts matrices M (one is shown in Fig. 2) are shaped like the matrices adapted for distribution by said distributing mechanism into the various channels of the several magazines, and, like them, they are formed with characteristically differentiated holes *m* for cooperating with the distributing mechanism as shown in said prior application. The holes are disposed upon said sorts matrices in such wise as to cause the switches 22 in the character determining part of the distributor to swing to the right, so that they may guide all of the sorts matrices into 20 the extreme left hand channel 21^a, from which they will fall into the left hand receiving throat of the magazine determining part of said distributor, that is, the part thereof which is mounted on the swinging frame.

Also the holes on these matrices are placed so that each one will cause such movement of the switches of the lower part of the distributor as will guide each sorts matrix 35 which is delivered into the left hand throat 25, into that one of the distributor channels 23^a, 23^b, 23^c or 23^d, which corresponds with the magazine containing matrices whose characters correspond in style with the characters 40 on the several sorts matrices.

Located respectively below the lower ends of these four left hand distributing channels 23 on the swinging frame are the upper matrix receiving ends of four tubes or conductors 26, which are fixed to the inner face of the left hand member of the swinging frame 10. Preferably these four tubes are formed as channels in the right face of a single metal plate 27 which is fixed to said 45 frame member, and the right side of said channels are all covered by a single cover plate 28 fixed to said channeled plate. These four tubes or conductors 26 are curved forward as they go down, and their lower ends 50 are so located that they will severally discharge into, or onto, the four sorts holders 30^a, 30^b, 30^c, 30^d. Each of these sorts holders consists of a narrow shelf 31, which extends horizontally to the left from its receiving 55 end onto which the associated tube will discharge the sorts matrices. And from its front edge this shelf inclines downward and joins with the upwardly and rearwardly inclined back wall 32. Preferably these four 60 sorts holders are made of a single piece of

metal which is connected to and extended to the right from the inner face of the left frame member of the swinging frame.

Associated with each of these four sorts holders is a packer 35. Each packer is fixed 70 to an endwise movable horizontal bar 36 which goes through and is slidably mounted in the left frame member of the swinging frame. A rock shaft 37 is mounted in bearings on the outer face of the left side member of the swinging frame, and it has four arms 38 which respectively engage with the four bars 36 to which the four packers 35 are connected. This rock shaft likewise has an arm 39 extended to a position such that 80 it may be engaged and moved in one direction by a rotatable face cam 40, and this rock shaft will be rocked in the opposite direction by a spring 41. The particular means for rotating the cam as shown in the 85 drawing consists of a belt 42 which goes from a driven pulley 43 mounted on a fixture, to a pulley 44 mounted on the side of the swinging frame near enough to the axis thereof to render the mechanism operative 90 in all positions of the swinging frame. Another pulley 45 is fixed to this upper pulley 44 referred to, and a belt 46, which goes over it, goes likewise over a pulley which is fixed to said cam. The rock shaft is kept 95 constantly oscillated so that the four packers 35 will be continuously vibrated from positions directly beneath the associated tubes to the left, so as to permit a matrix to drop from the tubes onto the sorts holders, and then to the right again to push said matrix and other matrices on the sorts holder to the right.

It is clear that the matrices in said sorts holders will be in such exposed condition 105 as will permit their ready withdrawal by hand, and that they will be arranged irrespective of character.

As previously stated, the invention is shown by way of example in a preferred 110 form particularly adapted for a particular machine. However, many modifications and alterations therein and in the mode of application will suggest themselves to those skilled in the art without departure from 115 its scope, and particularly in the case of this particular exemplification of the invention, it is not a matter of consequence whether the sorts holders and the tubes be placed at the right or left side of the swinging frame.

Having described my invention, I claim:

1. In a typographical machine, the combination of a swinging frame on which a plurality of matrix magazines are supported, 125 a plurality of sorts holders secured to the front side of said swinging frame, an equal number of conductor tubes mounted on said swinging frame with their upper ends arranged one behind another, and with their 130

lower ends arranged to discharge respectively into said several sorts holders, and distributing mechanism adapted to distinguish the sorts matrices and to discharge them into the upper ends of those conductor tubes which are associated with the sorts holders in which said sorts matrices severally belong.

2. In a typographical machine, the combination of a swinging frame on which a plurality of matrix magazines are supported, a plurality of sorts holders secured to the front side of said swinging frame, an equal number of conductor tubes mounted on said swinging frame with their upper ends arranged one behind another, and with their lower ends arranged to discharge respec-

tively into said several sorts holders, and distributing mechanism adapted to distinguish the sorts matrices and to discharge them into the upper ends of those conductor tubes which are associated with the sorts holders in which said sorts matrices severally belong, a packer located in the receiving end of each sorts holder, and mechanism carried by said swinging frame for operating said packer.

In testimony whereof, I hereunto affix my signature in the presence of two witnesses.

DAVID PETRI-PALMEDO.

Witnesses:

WALTER BUSWELL,
GILBERT B. FAYETTE.
